Primary Examiner — Cathron Brooks*Assistant Examiner* — Christian P McLean(74) *Attorney, Agent, or Firm* — Kirschstein, Israel, Schiffmiller & Pieroni, P.C.(57) **CLAIM**

The ornamental design for a bottle, as shown and described.

DESCRIPTION

FIG. 1 is a perspective view of a bottle according to my new design.

FIG. 2 is a front elevational view thereof.

FIG. 3 is a top plan view thereof.

FIG. 4 is a right side elevational view thereof.

FIG. 5 is a left side elevational view thereof.

FIG. 6 is a rear elevational view thereof; and,

FIG. 7 is a bottom plan view thereof.

The dash-dash broken lines shown in the drawings are included for the purpose of illustrating environmental structure and form no part of the claimed design.

The dot-dot-dash broken line shown at the top of the bottle defines the boundary of the claimed design, and forms no part thereof.
